(57) **CLAIM**

The ornamental design for a portion of a vehicle exterior, as shown and described.

DESCRIPTION

FIG. 1 is a front perspective view of a portion of a vehicle exterior showing our new design;

FIG. 2 is a rear perspective view thereof;

FIG. 3 is a side elevational view thereof with the opposite side being a mirror image;

FIG. 4 is a front perspective view thereof;

FIG. 5 is a rear elevational view thereof; and,

FIG. 6 is a top plan view thereof.

The broken line showing of the remainder of the vehicle including the tires and the steering assembly are for illustrative purposes only and form no part of the claimed design.
